UNITED STATES PATENT OFFICE.

JOHN K. PENNINGTON, OF LOS ANGELES, CALIFORNIA.

VENTILATOR CAP.

1,420,142.

Specification of Letters Patent. Patented June 20, 1922.

Application filed June 16, 1920. Serial No. 389,396.

To all whom it may concern:

Be it known that I, JOHN K. PENNINGTON, a citizen of the United States, residing at Los Angeles, in the county of Los Angeles, State of California, have invented new and useful Improvements in Ventilator Caps, of which the following is a specification.

This invention has to do with a ventilator cap, that is, a cap for ventilator flues or the like, and an object of the invention is to provide a simple, effective and compact device of this character which will operate to supply air to, and draw it from a ventilating system, or the like.

The present device or apparatus may be advantageously employed in connection with a ventilation system of the general character set forth in my co-pending application entitled "Ventilation system" filed May 29, 1920, Serial No. 385,213, although it will be understood that it is in no way connected, or limited, to any one such specific type or form of ventilation system, and in fact, is not necessarily limited to use in connection with a system or apparatus which is specifically a ventilation system. For purpose of illustration and in order to facilitate in the disclosure of the invention, I am herein setting it forth in connection with or as applied to, a ventilation system. It being understood of course that when I refer to a ventilation system that I do not necessarily limit or restrict myself to what is strictly or specifically known as a ventilation system.

A particular object of the invention is to provide a single unitary cap structure or device of the general character above set forth which will not only operate to supply air to a ventilation system but will also operate to draw air from a ventilation system; and further, to provide a cap for simultaneously performing such operations. The provision of a compact unitary cap of this character greatly reduces the number of caps required for a ventilation system and also materially reduces the cost of installing a ventilation system. The simultaneous supplying of air to and drawing of air from a ventilation system greatly increases the effectiveness of the system and is therefore of particular commercial importance.

A noteworthy feature of the present cap is the simple, slight, compact, and weather

proof construction. The simplicity and compactness of the device makes it slight, and its arrangement and formation of parts makes it rain and snow proof.

Various other objects and features of the invention, not herein specifically set forth or referred to, will be clearly understood from the following detailed description of a preferred embodiment of the invention throughout which reference is had to the accompanying drawings in which:

Fig. 1 is a side elevation of the cap provided by the invention; Fig. 2 is a front elevation of the cap being a view taken as indicated by line 2-2 on Fig. 1; Fig. 3 is a plan view of the cap showing it in one position in full lines and in another position in dotted lines to illustrate the manner in which it swings or positions itself to face directly into the wind; Fig. 4 is a more or less diagrammatic view of the cap in connection with a typical ventilation system such as it may be advantageously arranged in connection with; Fig. 5 is an enlarged detailed sectional view of the cap taken as indicated by line 5-5 on Fig. 3; Fig. 6 is a detailed sectional view taken as indicated by line 6-6 on Fig. 5; and Fig. 7 is a detailed sectional view taken as indicated by line 7-7 on Fig. 5.

Throughout the drawings numeral 10 designates the cap which is rotatably mounted on, or over, the upper ends of the intake flue 11 and exhaust flue 12 of the ventilation system 13. The ventilation system 13, which I am herein setting forth merely for a purpose of illustration, comprises ducts 14 connected with the intake flue 11 and opening into the upper portions of the rooms A and B, and ducts 15 connecting with the exhaust flue 12 and opening into the lower portions of the rooms A and B, as clearly shown in Fig. 4. At the point where the cap 10 is over the upper ends of the flues 11 and 12 they are cylindrical in cross-sectional configuration and are arranged concentrically one within the other, the intake flue 11 being within the exhaust flue 12. For simplicity and compactness of construction it is preferred that, at least, the upper end portions of the flues 11 and 12, where the cap 10 is mounted, be formed of sheet metal, as shown in the drawings.

The cap 10 comprises, generally, a horizontally disposed cylindrical body 20, a vertically disposed cylindrical flue 21, and suit-

ably arranged flues and ducts arranged within said body 20 and flue 21. The body 20 is open ended and, in fact, has flared or funnel shaped portions 22 at its ends. The upper end of the cylindrical flue 21 joins, and forms a tight joint with, the body 20 while its lower end extends downwardly over the upper end of the exhaust flue 12, in the manner shown in Fig. 5 of the drawings. The body 20 and cylindrical flue 21 are formed so that the flue opens into the body, thereby causing the upper open end of the exhaust flue 12 to be in direct communication with the interior of the body 20. The communication between the upper end of exhaust flue 12 and interior of body 20, however, is not totally unrestricted as there is a flue 24 extending from the upper end of the cylindrical flue 21 to the rear end portion of the body 20 and opening toward the rear of the cap. The flue 24 is suitably curved and is more or less diverging toward its open rear end, as clearly shown in Figs. 5 and 6 of the drawings. It will be noted in the drawings that the flue 24 is concentric with the body 20 and that its largest or rear portion is not sufficiently large to completely fill the body 20 but is of such size as to form or leave a small restricted portion 25 in the body 20 between the extreme end of the flue 24 and the inside of the body.

At the front or forward portion of the body 20 and within the body 20 is provided a suitably shaped and arranged flue 26 which is open at its forward end and which communicates with a vertical centrally arranged cylindrical duct 27. The duct 27 extends downwardly from the body 20 through the cylindrical flue 21 and into the upper end of the intake flue 11 of the ventilating system 13. Although the forward end of the flue 26 is open to allow free passage of air into the flue and through the duct 27, louvers or baffles 28 are arranged at the forward open end of the flue 26 in a manner to admit air into the flue 26 but to prevent the passage of rain or snow into the flue 26. The baffles 28 are transversely disposed members and are arranged in spaced relation but so as to overlap, as clearly shown in Fig. 5 of the drawings. The flue 27 is considerably smaller than the flue 24 and extends upwardly through a portion of the flue 24 and connects into the flue 26 above the center of the body 20. In the preferred form of construction the flue 27 extends well upwardly into the body 20 and the flue 26 is formed with a curved bottom wall 30 which extends upwardly from the front open portion of the flue 26 to the duct 27, as clearly shown in Fig. 5. In practice, the curvature of the bottom wall 30 is concentric with the pivotal mounting 31 of damper 32 so that the damper may be positioned, as indicated in dotted lines in Fig. 5, in a

manner to completely close the flue 26 and thereby prevent passage of air through it. The damper 32 is connected to a control chain 33 so that it may be easily and conveniently operated, although in practice it is preferred that it be kept at all times in its up or open position. The provision of the damper in connection with flue 26 is primarily to provide means for positively closing the intake passage way of the cap so as to positively prevent rain, or the like, from beating into the cap between or past the baffles 28. It will be noted in the drawings, particularly in Figs. 5 and 6 of the drawings, that the lowermost baffle 28^a is considerably larger than the other baffles 28 and that it extends upwardly and inwardly in the flue 26 considerably farther than do the baffles 28. Also, the baffle 28^a is spaced at its lowermost edge from the bottom of the body 20 thereby allowing water to escape from the flue 26, as indicated by the arrow W in Fig. 5. This construction positively prevents accumulation of water or moisture in the bottom of the body 20 or flue 26 and thereby prevents the cap from rusting out and prevents accumulation of water that might cause water to work its way into or downwardly through the flues of the ventilating system.

Having described the general arrangement and construction of the flue cap and its manner of arrangement in connection with the ventilator flues, I will proceed to describe a form of pivotal mounting that may be provided for the cap in order that it may rotate about a vertical axis and thereby be positioned to face into the wind. A hollow vertical stationary pivot post 40 is arranged to extend upwardly from the upper portion of the ventilator flues through the duct 27 and into the body 20 of the cap. This pivot post 40 is arranged concentrically relative to the ventilator flues and the duct 27 and is carried by a bracket 41 supported within the intake flue 11 just below the lower end of the duct 27 by a plurality of radially disposed spacers 42 which extend through the flues 11 and 12 and which are securely held in place by clamping nuts 43 screw-threaded on them and arranged at the insides and outsides of the flues 11 and 12 in the manner clearly shown in the drawings. It is preferred, although not necessary, that the spacers 42 connect to the bracket 41 by screw-threading into it, and that the pivot post 40 be connected to the bracket 41 by screw-threading into it. This particular form of construction is desirable in that it is simple, inexpensive and compact.

The weight of the cap 10 is carried at the upper end of the pivot post 40 by a suitable ball thrust bearing 45 and the cap 10 is kept or held concentric with the pivot post and the ventilator flues 11 and 12 by 130

the ball thrust bearing 45, by a bearing 46, and by the cooperation of rings 47 and 48 mounted on the flue 21 and the upper end of exhaust flue 12 respectively. The ball thrust bearing 45 comprises a ring like member 50 which is adjustably carried on the pivot post 40 near its upper end, and a ring like member 51 mounted or carried by the flue structure within the body 20.

10 The ring members 51 and 50 are separated by hardened steel balls 52 and the member 51 is formed with an annular projection 54 which engages or extends into a suitable annular groove formed in the member 50, to 15 keep or hold the two members 50 and 51 concentric. The bearing 46 engages the pivot post 40 about midway between its two ends and is carried or supported by the flue 21 in substantially the same manner as the 20 bracket 41 is carried by the ventilating flues. The bearing 46 preferably fits the pivot post comparatively loosely and is supported or carried by radially disposed braces 55 which extend through the duct 27 and the flue 21 25 and are held in place by clamping nuts 56 screw-threaded on them and arranged inside and outside of the duct 27 and flue 21, in the manner clearly shown in Fig. 5. In practice, the brace members 55 not only support 30 or carry a bearing 46 but also reinforce and hold the duct 27 centrally within the flue 21. The rings 47 and 48, which co-operate to hold the cap 10 centrally, relative to the flues 11 and 12, are permanently or securely 35 carried on the flue 21 and the upper end of flue 12, respectively, and are formed so that a portion of the ring 47 extends or fits over the upper portion of ring 48, in the manner clearly shown in Fig. 5. The rings 47 and 40 48 as well as holding the cap 10 in place form a tight joint between the portion 21 and the upper end of the exhaust flue 12 and thereby prevent moisture from working its way, or getting, into the flue 24 or the exhaust 45 flue 12. The importance of the joint between the flue 21 and exhaust flue 12 being tight will be best understood from the following description of the operation or action of the apparatus.

50 With the cap 10 mounted in the manner just set forth it will be readily understood how it will freely swing or turn about the pivot post 40 and that, with the various joints, or points of connection, properly adjusted it will rotate very easily. The cap is 55 designed to at all times face into the wind in order that it will properly operate and for this reason a longitudinally disposed vertical fin 60 is arranged to extend upwardly 60 from the body 20, and outwardly and rearwardly extending rudder members 61 are arranged to extend from the rear end of the fin 60. The rudder members 61 may be 65 suitably braced by brace members 62 and by being arranged to extend outwardly and

rearwardly from the rear end of the fin 60, are particularly effective in co-operating with the fin 60 to cause the cap to face and stay faced squarely into the wind.

In operation, wind, or currents of air, acting upon the fin 60 and rudder members 61 face the cap so that its open front end C faces squarely into it. Therefore, considerable air is caught, by the flared or funnel shaped portion 22 at the front of the cap, 70 and is directed into the flue 26, past the baffles 28 and 28^a, and around the flue 26 through the body 20. The air upon entering the flue 26 is baffled or directed upwardly and rearwardly by the baffles 28 and passes 80 through the flue 26 and into the duct 27. The air upon entering the duct 27 passes downwardly through it and into the intake flue 11 of the ventilating system. From the flue 11 of the ventilating system the air may 85 be distributed or circulated in any suitable manner as may be required by the particular ventilating system in connection with which the cap is arranged. The fact that the lower end of the duct 27 extends into 90 the upper end of the intake flue 11 prevents the escape of air from the joint between the duct and flue without making it necessary to make a closed or tight joint between the duct and flue.

95 The air which does not pass through flue 26, but which passes through the body 20 around the flue 26, flows rearwardly through the body 20 and discharges from, or flows out of, the open rear end D of the body 100 20. The cap is constructed so that a considerable volume of air is admitted into the body 20 thereby causing the velocity of the air at the restricted portion 25, between the rear end of the flue 24 and the body 20, 105 to be comparatively high. Further, the flared or funnel shaped portion 22 of the body 20 at the rear of the body also acts to materially increase the velocity of the air at the restricted portion 25 and at the rear 110 of the cap as it tends to more or less reduce the pressure of the air at the rear of the cap. It will be readily understood how the air passing around the rear end of flue 24 at a very high velocity draws air from the flue 115 24 and therefore draws air upwardly through the flue 21 and the exhaust flue 12 of the ventilating system. In practice the air is very effectively drawn upwardly through the flue 12, flue 21, and from the 120 flue 24 by this action. It will be readily understood how the exhaust flue 12 may be connected with suitable parts of the rooms or how the exhaust flue 12 may be connected with a suitable exhaust system of any 125 ventilating system; for instance, it may be arranged in connection with a system such as is illustrated in Fig. 4 of the drawings.

In order that the ventilating system may operate at times when there is little or no 130

wind, or circulation of air, an electric fan 70 is arranged in the intake flue 11 just below the bracket 41 so that air may be mechanically drawn into the cap and forced downwardly through the intake flue thereby causing clear fresh air to be drawn through the cap and discharged or distributed into the ventilating system. It will be understood of course that the electric fan 70 need only be operated when there is practically no wind or circulation of air, and further, that under certain circumstances, or in certain localities, it may be unnecessary to provide the fan 70.

From the foregoing description it will be understood how the cap 10 is entirely automatic, except for the operation of the damper 32, and that it is extremely simple and therefore requires very little, in fact, practically no care or attention. The damper 32 being an element used only upon rare occasions does not in any way complicate the cap or make it inconvenient to operate. In the particular form of the invention shown in the drawings the pivot post 40 is hollow and the control or operating chain for the damper 32 is arranged over suitable pulleys 80 and 81 so that it will hang downwardly through the pivot post and thereby be out of the way of the operating part and in a position from which it can be conveniently conducted or extended to the point from which it is desired to control the cap.

Having set forth merely a preferred embodiment of my invention, I do not wish to limit or restrict myself to the particular details hereinabove set forth but wish to reserve to myself any variations or modifications that may appear to those skilled in the art and fall within the scope of the following claims.

Having described a preferred form of my invention, I claim:

1. In combination a stationary intake flue, a stationary exhaust flue, and a rotatable cap comprising an open ended body, an inlet flue extending from the forward part of the body to the intake flue and being open at the forward part of the body, and an outlet flue extending from the exhaust flue to the rear part of the body and being open at the rear of the body, the inlet and outlet flues being arranged in the body to leave a continuous passage through it.

2. In a cap of the character described adapted to be arranged in connection with an intake flue and an exhaust flue, and open ended body, an inlet flue arranged from the front of the body to the intake flue, said inlet flue being open at the front end of the body, and an outlet flue arranged from the exhaust flue to the rear of the body, said outlet flue being open at the rear of the body, the inlet and outlet flues being arranged in the

body to leave a continuous passage through it with a restricted portion at the open end of 65 the outlet flue.

3. In a cap of the character described adapted to be arranged in connection with an intake flue and an exhaust flue arranged one within the other, an open ended body, 70 an inlet flue arranged between the front of the body and the intake flue, said inlet flue being open at the front of the body and being arranged to extend into the intake flue, an outlet flue arranged between the exhaust flue 75 and the rear of the body, the outlet flue being open at the rear of the body and arranged to extend over the exhaust flue, the inlet and outlet flues being arranged in the body so that part of the air entering the front end 80 of the body enters the inlet flue, and so that there is a continuous passage through the body with a restricted portion at the open end of the outlet flue.

4. In a cap of the character described 85 adapted to be rotatably mounted over the ends of vertically arranged intake and exhaust flues arranged one within the other, a horizontally disposed open ended body, an inlet flue extending from the front of the body to the intake flue, said inlet flue being open at the front of the body and arranged to extend into the intake flue, an outlet flue extending between the exhaust flue and the rear of the body, said outlet flue being open 90 at the rear of the body and being arranged to extend over the exhaust flue, the inlet and outlet flues being arranged in the body so that air will be caught by the open end of the inlet flue and so that there is a passage 100 through the body with a restricted portion around the open end of the outlet flue, means for preventing water, or the like, from entering the inlet flue, and means to keep the front end of the body facing into the wind. 105

5. A cap of the character described comprising a horizontally disposed open ended body, a vertically disposed flue portion in connection with the central portion of the body, an outlet flue arranged in the body 110 from the vertical flue to its rear end, an inlet flue arranged in the body and vertical flue to have an open end at the front of the body and to extend downwardly through the vertical flue, and means for rotatably mounting the cap over two vertically disposed ventilating flues arranged one within the other so that the vertical flue portion connects with the outer ventilating flue and so that the inlet flue connects with the inner 115 120 ventilating flue.

6. A cap of the character described comprising, a horizontally disposed open ended body, a vertically disposed flue portion in connection with the central portion of the body, an outlet flue arranged in the body to 125

extend from the vertical flue to the rear end of the body, said outlet flue being open at the rear of the body and being shaped to diverge toward its open end to form a restricted portion in the body at its rear end, an inlet flue arranged in the body to extend from the front end of the body to and downwardly through the vertical flue, said inlet flue being open at the front of the body and arranged to extend upwardly and inwardly in the body before extending downwardly through the vertical flue.

7. A cap of the character described comprising, a horizontally disposed open ended body, a vertically disposed flue portion in connection with the central portion of the body, an outlet flue arranged in the body to extend from the vertical flue to the rear end of the body, said outlet flue being open at the rear of the body and being shaped to diverge toward its open end to form a restricted portion in the body at its rear end, an inlet flue arranged in the body to extend from the front end of the body to and downwardly through the vertical flue, said inlet flue being open at the front of the body and arranged to extend upwardly and inwardly in the body before extending downwardly through the vertical flue, means at the open end of the inlet flue to allow passage of air into the flue and prevent passage of water, or the like, into the flue, control means in connection with the inlet flue, and means for rotatably mounting the cap over two vertically disposed ventilating flues arranged one within the other so that the vertical flue portion connects with the outer ventilating flue and so that the inlet flue connects with the inner ventilating flue.

40 8. A cap of the character described comprising, a horizontally disposed body having diverging open ends, a vertically disposed flue portion in connection with the central portion of the body, an outlet flue arranged in the body to extend from the vertical flue

to the rear end of the body, said outlet flue being open at the rear of the body and being shaped to diverge toward its open end to form a restricted portion in the body at its rear end, and an inlet flue arranged in the body to extend from the front end of the body to and downwardly through the vertical flue, said inlet flue being open at the front of the body and arranged to extend upwardly and inwardly in the body before extending downwardly through the vertical flue.

9. A cap of the character described comprising a horizontally disposed open ended body, a vertically disposed flue portion in connection with the body, an outlet flue arranged in the body to extend from the vertical flue to the rear of the body, the outlet flue being open at the rear of the body and being shaped to diverge toward its open end to form a restricted portion in the body, and an inlet flue arranged to extend from the front of the body downwardly through the vertical flue.

10. In a cap of the character described, a horizontally disposed open ended body, a vertically disposed flue portion in connection with the body, an outlet flue arranged in the body to extend from the vertical flue to the rear of the body and being open at the rear of the body, and an inlet flue arranged in the body to extend from the front of the body to and downwardly through the vertical flue, said inlet flue being open at the front of the body and arranged to extend upwardly and inwardly from the front of the body before extending downwardly through the vertical flue.

In witness that I claim the foregoing I have hereunto subscribed my name this 11th day of June, 1920.

JOHN K. PENNINGTON.

Witness:

VIRGINIA I. BERINGER.
